UNITED STATES PATENT OFFICE.

SEYMOUR C. PALMER, OF SOUTH NORWALK, CONNECTICUT.

HAT-SIZING MACHINE.

SPECIFICATION forming part of Letters Patent No. 320,581, dated June 23, 1885.

Application filed January 13, 1885. (No model.)

To all whom it may concern:

Be it known that I, SEYMOUR C. PALMER, a citizen of the United States, residing at South Norwalk, in the county of Fairfield and State 5 of Connecticut, have invented certain new and useful Improvements in Hat-Sizing Machines; and I do hereby declare the following to be a full, clear, and exact description of the invention, such as will enable others skilled in the 10 art to which it appertains to make and use the same.

My invention relates to certain novel and useful improvements in machines for sizing fur hats, and has for its object to provide a 15 machine for this purpose which shall automatically perform the function of sizing, and which may be regulated so as to continue this operation for a longer or shorter time, as may be desired; and furthermore, my invention 20 has for its object to treat the "roll" after the manner of hand manipulation, and to remove the particles of fur uniformly without the formation of the so-called "lightning-rods" or "crow-feet" in the hat.

With these ends in view my invention consists in the several details of construction and combination of elements, hereinafter fully explained, and then specifically designated by 25 the claims.

In order that those skilled in the art to which my invention appertains may understand more fully how to make and use my improvement, I will proceed to describe the same in detail, referring by letter to the accompanying drawings, forming a part of this 35 specification, in which—

Figure 1 is a central vertical cross-section of my improved machine; Fig. 2, a front elevation, one end of the machine being broken 40 away; and Fig. 3, an end elevation of my improvement above the horizontal plane of the bed.

Similar letters denote like parts in the several figures of the drawings.

In the art of hat-sizing it is necessary, in 45 order to produce a superior article of manufacture, to conform to the following conditions: First, to compress the hat-roll with a rolling movement, gradually relieving the compression at the end of said movement, a slight pressure being brought to bear upon the roll

to move it backward to a position for further manipulation; second, to be careful to manipulate work of the same nature throughout the same time, and with a uniform degree of 55 pressure of the sizing-surfaces. Various machines have been devised to accomplish this purpose, but it is obvious that nothing but an automatic construction can perform the desired functions in accordance with the conditions above mentioned. Very often during the process of hand-sizing the workmen inadvertently oversize the hats, especially if their minds are preoccupied, and it is with a view to overcome these difficulties that the present 60 machine is constructed.

Are uprights or standards, which form the two ends of the machine, and are secured together by the brace-frame B and rods C. In the tops of these standards are slots D, in 70 which are fitted boxings E, so as to have a free vertical movement, the object of which will be presently explained.

Journalized within the boxings E is the rock-shaft F, extending out at either end of the 75 machine, (but one end being shown in the drawings,) and supported by connecting-rods G, the lower ends of which are in turn supported by crank-pins H. These pins are secured to adjustable levers I, which are ful-

crumed at J to the disks K.

The free ends of the levers I are slotted at L, and through these slots and into the disks K pass bolts M. The object of this construction is to give the crank-pins more or less 85 throw, which is accomplished by simply loosening the bolts M and moving the levers I to or from the center of the disks, and again tightening the bolts, thereby securing the levers in the required position. The disks K are secured on the outer extremities of driving-shaft N, which is journalized in the standards above the center of the machine and in vertical alignment with the rock-shaft F.

Are oscillating hangers keyed or otherwise 95 rigidly secured on the rock-shaft, and extending down below the driving-shaft. The lower ends of these hangers are connected by slabs of wood or other material forming the upper sizing-surface of the machine, which is preferably roughened, as seen in section in Fig. 1.

In the center of one or both of the hangers

are formed guide-ways P, in which are fitted boxings Q, adapted to slide vertically therein.

R is a crank formed on or secured to the driving-shaft. This crank passes through and has its bearing in the boxing Q, so that it will be readily understood that when the driving-shaft is caused to revolve the crank R will cause the hangers O to oscillate back and forth, the center of oscillation being the rock-shaft F, and at the same time the crank-pins H, through the connecting-rods G, will raise and lower said rock-shaft. The hangers being secured to the rock-shaft, it will be obvious, therefore, that at every revolution of the driving-shaft said hangers and the sizing-surface attached thereto will be caused to oscillate, as described, and at the same time have a vertical reciprocating motion, the object of which will be presently explained.

20 S are slide-frames running in guide-ways T, formed in the brace-frames B. To these slide-frames are adjustably secured triangular frames U by means of headed bolts V, passing through slots W in the frames U and into the frames S.

25 X is an adjusting-screw the shank of which passes through and is swiveled or collared to the block Y, cast with the frame U. This screw passes downward and engages with threads in a block, Z, forming a part of the slide-frame S. By manipulating the screw X the slide-frame will be raised or lowered, as the case may be, the object of which will be hereinafter explained.

30 A' are bracket-ribs secured to the upper portion of the slide-frames and extending out on either side of the machine at right angles to its length.

B' are four frames, which are supported by plate-springs C' C' placed upon the ribs A'.

40 To the frames B' are secured sizing-surfaces D', which may or may not be roughened, as desired. These surfaces form an arc of a circle described from the center of the rock-shaft F.

45 E' are brackets, four in number, bolted to the standards A.

F' are ratchet-wheels, journaled to said brackets by means of short shafts G'.

50 H' are grooved pulleys secured to and concentric with the ratchet-wheels. Around these pulleys are cords I', which support weights J', by which the pulleys and ratchets are revolved backward when released, as will be explained.

55 K' are bell-crank levers, pivoted on the short shafts G', the lower ends extending downward and inward and terminating in forks L', between which are pivoted guide-tubes M'. The upper ends of said levers extend upward, and 60 are slotted at their extremities.

N' are long sliding bolts fitted in lugs O' projecting from the brackets. Secured to said bolts are studs P', from which project pins Q' into the slots in the upper extremities of the 65 bell-crank levers K', so that any movement of the bolts will operate said levers.

R' are lugs projecting from the faces of the triangular frames U, under which the bolts N' latch to retain the frame in an elevated position while the hat-roll is being acted upon.

70 S' are retaining gravity-pawls pivoted to the brackets and having heel ends extending up within the plane of the movement of pins T' projecting from the bolts N'. To the rock-shaft F, just inside of the standards, are secured small walking-beams U', whose ends are forked, and have pivoted therein heads V', in which are secured the upper ends of rods W'. These rods extend downward, their lower ends passing through the guide-tubes M', and are 80 free to slide therein.

X' are pawl-boxes, secured to the rods W' by means of set-screws.

85 Y' are slide-pawls, set in the boxes X' and actuated by coil-springs Z', placed behind them. Within the boxes A' are holes in the faces of the ratchet-wheels adapted to receive the pins B'.

90 C' are studs secured to the ratchet-wheels and adapted to strike against lugs D' on the under side of the bolts N', in the backward rotation of the ratchet-wheels, as will be presently explained.

95 E' are treadles pivoted to the lower lugs of the standards, their inner ends being provided with spring-actuated bolts F'.

100 G' are extensions of the triangular frames U, and when the latter are in their lowered position said extensions rest on the bolts F' of the treadles. When the treadles are operated to raise the frames U, their inner ends will describe circles from their pivotal points, and when said frames have been raised to the required height the bolts will pass from under the extensions and the frames drop till arrested by the lugs R' catching on the bolts N'.

105 From the foregoing description, the operation of my improved sizing-machine will obviously be as follows: The driving-shaft N is caused to revolve by a belt connecting the 110 pulleys H' I' (fast and loose) on said shaft with any convenient counter-shaft. As this shaft revolves, the oscillating hangers and upper sizing-surface attached thereto will be caused to move back and forth and up and 115 down, as herein before set forth. The hat-roll is placed upon one of the sizing-surfaces D', of which there are four, each having independent operating mechanism and an attendant. Now, by operating one of the treadles 120 E', the triangular frames, sliding frame, and sizing-surface corresponding to said treadle will be thrown up until the bolt N' slides under the lug R' and retains the above-named parts in this elevated position, which brings 125 the hat-roll on this surface in the field of operation of the upper sizing-surface, which acts upon it after the manner of hand-sizing, exerting considerable pressure through the forward stroke, then ceasing this pressure almost 130 entirely, leaving only enough on the backward stroke to carry the roll back for a repe-

tition of the operation. At each rise and fall of the oscillating shaft the rods W' operate the pawls and cause the ratchet-wheels to turn one tooth, so that it will be readily understood 5 that at every operation of the upper sizing-surface on the hat-roll the ratchet will be turned one tooth, which will advance the stud C² a like distance, until being moved step by step it strikes the lug D², withdrawing the bolt N' from under the lugs R', when the sizing-surface, being supported by said lug, as before explained, will drop by gravity until arrested by the treadle or other convenient stop. Thus the hat-roll is taken without the 15 field of action of the upper sizing-surface automatically. When the bolt N' is withdrawn by the stud C², the upper end of the bell-crank lever K' will be caused to move backward by its connections with said bolt, as 20 above set forth, thus causing the lower end of said lever to move inward, which, acting as a guide for the rod W', will throw the pawl Y', carried by said rod inward, so that the actuation of said pawl will not operate the ratchet. 25 It will be seen that by this construction each bed or lower sizing-surface is entirely independent of the others, as one or any of the pawls Y' may be thrown out of engagement with the ratchet without affecting the others; also, 30 by the backward movement of the bolt N' the retaining-pawl S' is drawn out of engagement with the ratchet, as hereinbefore explained, thus allowing the weight to turn said ratchet backward till the pin B² strikes the lug D² 35 forcing the bolt inward and stopping said ratchet, and restoring the operating mechanism to its normal position for a repetition of the above when the hats have been crozed and replaced on the bed or lower sizing-surface. 40

The time that the hat-roll is acted upon before the dropping of the bed is determined by the position of the pin B²—for instance, if the pin B² be in the second hole of the series, as 45 shown in the drawings, and in its normal position against the lug D², the stud C² will be, say twenty teeth of the ratchet away from the lug D². The pawl Y' will therefore have to operate the ratchet twenty times before the stud C² will strike said lug and withdraw the bolt N', which will allow the bed to drop and the ratchet to return to its normal position, as before explained. 50

If it is desired to operate on the hat-roll, 55 more or less, it is only necessary to change the pin B² in the series of holes A², so that the normal position of the stud C² will be farther from or nearer to the lug D².

If at any time during the manipulation of 60 the machine the hat-roll should be inserted wrongly, or from any other cause it should become necessary to drop the bed before the automatic mechanism did so, it is only necessary for the operator to grasp the handle P' and withdraw the bolt, when the result will be 65 the same as when said bolt was withdrawn by the action of the stud C².

I do not wish to be confined to any particular kind of mechanism or combination of parts for effecting the automatic operation of the 70 lower sizing beds or surfaces, since I am enabled to accomplish this result in many ways, the gist of my invention in this respect resting in the broad idea of producing a machine of this description in which the duration of 75 the sizing operation shall be perfectly automatic, while at the same time it may be regulated and is furthermore capable of being limited by the operator at any time.

Having thus fully described my invention, 80 what I claim as new and useful, is—

1. In a hat-sizing machine, a single upper sizing-surface in combination with one or more hat-roll supports capable of vertical adjustment and adapted to be lowered without 85 the field of action of said surface, and means for automatically imparting to the upper sizing-surface a simultaneous oscillating and vertically-reciprocating movement, whereby the hat-roll is revolved, and at the same time 90 compressed after the manner of hand-sizing, substantially as set forth.

2. In a hat-sizing machine, an upper sizing-surface adapted to be automatically oscillated transverse to the hat-roll, in combination with 95 means for automatically raising and lowering said surfaces simultaneously with the oscillation, substantially as set forth.

3. In a hat sizing machine, the upper sizing-surface adapted to be oscillated, and at the 100 same time have a vertical reciprocation, whereby the hat-roll is revolved and compressed, substantially as set forth.

4. In a hat-sizing machine, the combination, with lower sizing-beds adapted to be dropped automatically, of an upper sizing-surface constructed and arranged to have two movements—namely, an oscillation transverse to the lengthwise direction of the hat-roll, and a vertical reciprocation, whereby said roll may 110 be operated upon and then relieved from pressure after the manner of hand-sizing, substantially as shown and described.

5. In a hat-sizing machine, the combination, 115 with the power-shaft which operates the upper sizing-surface of the hat-roll supports, means connected to said shaft for automatically dropping said supports at a predetermined time, and the upper sizing-surface capable of simultaneous oscillatory and vertically reciprocatory movements, substantially 120 as set forth.

6. In a hat-sizing machine, the driving-shaft having arranged thereon the lifting-crank and oscillating-crank, in combination 125 with the rock-shaft, hangers, and sizing-surfaces, as specified.

7. In a hat-sizing machine, the driving and oscillating shafts connected by rods G, the latter shaft supporting the hangers and imparting a vertical reciprocation thereto, while the crank R on the former gives said hangers an oscillatory movement, in combination with 130 the sizing-surfaces adapted to be separated

automatically, and means for restoring said surfaces to their juxtaposition, as and for the purpose set forth.

8. In a hat-sizing machine, the upper sizing-surface operated as described, in combination with the lower sizing-surfaces, independent of each other, adapted to be elevated by the treadles E², and retained in an elevated position by the bolts N', said bolts being under the control of automatic mechanism for withdrawing the same, as shown and described.

9. In a hat-sizer, the upper sizing-surface in combination with the independent lower sizing surfaces, the bolts N', operated by the ratchet-wheels and operating the bell-crank levers, and retaining-pawl to free said ratchet and allow them to return to their normal position, as and for the purpose set forth.

10. The herein-described combination of

the upper and lower sizing-surfaces, the former having an oscillating and vertically-reciprocating movement, the latter being actuated by the treadles E², bolts N', and ratchet-wheels F', as specified.

11. In combination with the lower sizing-surfaces or beds of a hat-sizer, the bolts N', ratchet-wheels F', actuated by the pawls Y', and revolved backward by the weights J', bell-crank levers K', and retaining-pawl S', both connected to and operated by the bolts N', substantially as and for the purpose specified.

In testimony whereof I affix my signature in presence of two witnesses.

SEYMOUR C. PALMER.
